UNITED STATES PATENT OFFICE.

ALPHEUS W. ALTORFER, OF PEORIA, ILLINOIS, ASSIGNOR TO ALTORFER BROS. COMPANY, OF EAST PEORIA, ILLINOIS, A CORPORATION OF ILLINOIS.

CENTRIFUGAL DRIER.

Application filed May 4, 1927. Serial No. 188,686.

This invention has reference to washing machines and particularly to that type, in which is employed a centrifugal extractor for removing the free water from the clothing or other materials by centrifugal action, and discharging such water onto a manually and circumferentially adjustable drain board for directing such water into the washing tub or other receptacle, and which also functions to catch the drippings from clothing or other materials passed from the tub or other receptacle to said extractor.

The invention comprehends a housing mounted at the head of the extractor in a manner to adapt it to be manually and circumferentially adjusted about the extractor, whereby to selectively position the drain board over, and to direct water extracted from clothing or other materials, to the washing tub or other receptacle or receptacles; and it is the principal object of this invention to provide a new and novel mounting for such housing whereby it is placeable and removable from its support in a predetermined position circumferentially of its support; means being provided to prevent wabbling, rattling or chattering of the housing on its support and means being also provided for locking the housing in different circumferential positions on its support.

That the invention may be more fully understood, reference is had to the accompanying drawings illustrating a preferred embodiment of the invention, in which:

35 Fig. 1 is a plan view, on a greatly reduced scale, of so much of a washing machine, including the extractor, as will illustrate the embodiment of my invention, the housing and its drain board shown in full and dotted lines in two of its circumferential positions;

40 Fig. 2 is an elevation partly in section of what is shown in Fig. 1;

Fig. 3 is a plan view, on a somewhat larger scale than is Fig. 1, and illustrates the support for the housing (which has been removed), the dotted position of the drain board showing the preferred predetermined position for placing and removing such board and its housing;

45 Fig. 4 is a bottom plan view, partly in section, of the housing and drain board, being on the same scale as its support in Fig. 3 and shows the anti-rattling or anti-chattering means and also the locking means;

50 Fig. 5 is a sectional detail of the locking

means as the same would appear if taken on the line 5—5, Fig. 4.

Fig. 6 is a detail perspective view, partly in section, of the support for the housing and as the same would appear on the line 6—6, 60 Fig. 3, and

Fig. 7 is a sectional view of the housing support with the housing in dotted lines mounted thereon and its locking means, as the same would appear if taken on the line 65 7—7, Fig. 3.

Like characters of reference denote corresponding parts throughout the figures.

In the drawings I have illustrated only so much of a washing machine including washing tub, centrifugal extractor and supporting frame as will show the practical embodiment of my invention. In Figures 1 and 2 there is illustrated by dotted lines a receptacle to show the adaptability of my invention in the 75 passage of clothing or other materials into the extractor from a washing tub and other receptacle and the discharge of water expelled from the extractor into such tub or receptacle.

The washing tub, only a part of which is shown, is designated 1 having a washing element 2 adapted to be operated from a shaft 3 rotatably journaled through the bottom of said tub. The head frame 4 for the tub 1 terminates in a laterally extended ring-like extension 5 the axis of which, while being spaced at a suitable distance from one side of the tub is also off-set from a line extending transversely through the axis of the tub, 80 whereby to position the extractor closer to one side of the machine than the other for the convenience of the attendant in handling the washing and drying operation. A standard or post 6 supports the extension 5. The 85 legs or standards for the tub and connecting braces with the post 6 are omitted.

The ring-like extension 5 of the frame, which supports the housing and drain board connected thereto and which is manually 100 and circumferentially adjustable thereon is formed or provided with a vertically disposed annular flange 7, the peripheral surface of which is tapered downwardly and inwardly, as at 8, see Figs. 2 and 6; with the 105 exception that at predetermined, preferably three points the periphery of this flange is cut-away, as at 9, to provide cut-away or cut-out portions of suitable length with shoulders 10 at the opposite ends of such cut-away or 110

cut-out portions. Such an arrangement of ring-like extension and flange produces or provides an annular shelf portion 11 encircling the flange 7 to provide a rest for the water conducting housing, to be described, and on which the same may be rotated.

The housing to which reference has been made is designated 12 and is best seen in Figs. 1, 2, 4 and 5, respectively. Such housing is of suitable depth and circular in outline, being of outside diameter equal to the diameter of the ring-like extension 5 with bearing surfaces adapted to rest and rotate on the flange 7 and the shelf portion 11, see Figs 2 and 7. Said housing has an annular conduit 13, see Figs. 2 and 5, formed by its vertical outside wall 14 in spaced relation to a comparatively short upstanding inner wall 15. The outside wall 14 is formed with a depending apron 16 adapted to rest and rotate on the shelf portion 11, see Fig. 7, and the bottom 17 of the conduit 13, at a point coincident with the base of the wall 15, see also Fig. 5, is formed or provided with an annular shoulder or off-set 18 to overlap the flange 7, whereby the bottom 17 rests and rides on the top of said flange 7 with the apron 16 lying without and next adjacent the outside of the ring-like extension 5 and the shoulder or off-set 18 lying within and next adjacent the flange 7. In this manner and by this means the housing is seated and adapted to be rotated on the extension 5. The top of the housing is open, as at 19, and movable therein is a cover 20 for the extractor 21; said cover being rotatably connected to a support 22 hinged at one end to the housing, as at 23, while its opposite end is adapted to be locked against the housing, by suitable locking means 24.

In the form shown, the housing 12 is provided with a radially extended shelf portion 25, adapted through rotative movement which may be imparted to the housing 12, to be moved over the tub 1 or over a receptacle A, indicated by the dotted lines in Figs. 1 and 2. Over this shelf portion clothes and other materials may be moved to deposit the same in the extractor 21, from either the tub 1 or the receptacle A, or vice-versa, and such shelf will catch drippings and direct the same into the tub 1 or the receptacle A. The shelf 25 is partitioned to provide a conduit 26 therewithin in communication with the conduit 13 of the housing and having a discharge outlet, at its outer end, see Fig. 4, whereby water expelled from the receptacle 21 into the conduit 13 of the housing may be discharged into the tub 1 or the receptacle A, as it is believed will be understood.

The receptacle 21, is of the usual tapered-like container used in machines of like character and is operatively connected with an operating shaft 27, adapted to be actuated from the same source of power, not shown,

for operating the shaft 3 connected with the washing element 2. The upper end of the container or receptacle 21 is so positioned in relation to the interior of the housing 12, that through the centrifugal action set up by the rotation thereof, the water expelled thereby will overflow or be discharged over the top thereof, over the wall 15 of the housing 12 into the conduit 13 and be conducted thereby to the outlet within the shelf portion 25 forming the drain board, and from thence into the tub 1 or the receptacle A.

Connected to the inner face of the apron 16 of the housing are a plurality of spacing and anti-rattling or anti-chattering blocks 28, see Figs. 4 and 5. There are preferably three of these blocks, which have inner tapered surfaces, as at 29 and their lengths conform to or are slightly less than the length of the cut-away or cut-out portions 9 in the flange 7 of the housing. Preferably two of these blocks are fixedly attached to the apron 16 by the removable screws 30 and the remaining block is preferably laterally movable through and by means of a locking screw 31, see Figs. 4 and 5. These blocks are spaced from each other circumferentially of the housing to correspond to the spacing of the cut-out or cut-away portions 9 in the flange 7, so that when the housing is made to overlie the extension 5 and the blocks 28 and cut-out portions 9 are coincident, the housing may be dropped into assembled position on the extension 5 with the blocks 28 entering the cut-out portions 9 between the shouldered ends 10, and by reason of the inner faces of said blocks having the same taper as the peripheral surface 8 of the flange 7, the housing may then be rotated on the extension 5 with the tapered faces of the blocks and the tapered surface of the flange being next adjacent. These blocks will prevent rattling or chattering of the housing on its support during the rapid rotation of the container or receptacle 21. To lock the housing on its support, in any of its adjusted positions, the attendant will turn up the locking screw 31 forcing the block into impinging locking engagement with the flange 7. In Fig. 3 the dotted position of the shelf portion 25 of the housing shows the position it should be caused to assume when placing or removing said housing from its support.

The securing means for the housing will prevent its accidental displacement and provides a simple and convenient means of assembly and a means for fixing the same in adjusted positions, while providing for the easy removal of the housing for shipping purposes.

What I claim is:—

In a centrifugal extractor, in combination, a rotatable receptacle, a member supported to be manually and circumferentially adjusted about said receptacle for receiving water

- expelled thereby and for discharging such water at different points about said receptacle, a support for said member having an annular vertically disposed ring provided
- 5 with a tapered periphery having cut-out portions at predetermined points, spacing and non-chattering blocks carried by the member and so positioned circumferentially thereof as to be movable in the cut-out portions of
- 10 said ring when placing said member on and removing the same from said support and said blocks having tapered surfaces corre-
- sponding to the taper of the surface of said ring and for preventing dislodgment of the member from its support when said tapered surfaces of the ring and blocks are co-adjacent, and means co-acting with one of said blocks for locking such block in impinging relation with the ring of said support for securing said member in different circumferential positions thereon.
- In witness whereof, I have hereunto affixed my hand this 30th day of April, 1927.
- ALPHEUS W. ALTORFER.
